MEMORIAL GRAVE MARKER

John M. Lucken and Richard R. Clemmer, Minneapolis, Minn., assignors to Remembrance Memorials, Inc., Minneapolis, Minn., a corporation of Minnesota

Filed Mar. 13, 1961, Ser. No. 64,239

Term of patent 14 years

(Cl. D79—2)

FIG. 1

FIG. 2

FIG. 1 is a top plan view of a memorial grave marker, showing our new design;

FIG. 2 is a perspective view thereof showing the covers in a raised position;

FIG. 3 is a sectional view taken on the longitudinal centerline of the memorial grave marker shown in FIG. 1; and

FIG. 4 is an end elevational view of the memorial grave marker with the covers in closed position.

We claim:

The ornamental design for a memorial grave marker, substantially as shown.
